UNITED STATES PATENT OFFICE.

JAMES WILLIAMSON, OF CHICAGO, ILLINOIS, ASSIGNOR TO R. WILLIAMSON & CO., OF CHICAGO, ILLINOIS, A CORPORATION OF ILLINOIS.

HOLDER FOR ELECTRIC-LIGHT SOCKETS.

1,284,012.

Specification of Letters Patent.

Patented Nov. 5, 1918

Application filed August 12, 1915. Serial No. 45,230.

To all whom it may concern:

Be it known that I, JAMES WILLIAMSON, a citizen of the United States, residing at Chicago, in the county of Cook and State of Illinois, have invented a certain new and useful Improvement in Holders for Electric Light Sockets, of which the following is a full, clear, concise, and exact description, reference being had to the accompanying drawings, forming a part of this specification.

My invention relates to holders for electric light sockets and especially for holding incandescent lamp sockets.

The principal object of the invention is to provide a holder which can accommodate either an ordinary wall socket or a key socket or a socket with a chain pull, thus making the single construction of holder capable of use in connection with any one of said sockets.

In the accompanying drawings Figure 1 is an elevation of a holder for electric light sockets embodying my present invention, said holder being provided with a socket having a chain pull;

Fig. 2 is a view of the holder by itself;

Fig. 3 is a view of the holder provided with a key socket;

Figs. 4 and 5 are respectively side elevation and bottom plan views of a socket holder having means for detachably engaging the globe or shade.

Referring first to Figs. 1, 2 and 3, I show a holder 1 for an electric lamp socket, comprising a shell or casing more or less bell shaped as shown. The holder which is usually made of metal, is provided with a side slot 2 which is preferably substantially

vertical, with a side recess or enlargement 3 at its upper end. A pin 4 is shown at the top of the holder 1, said pin being understood to be screw threaded so as to detachably engage the socket inside of the holder. In Fig. 1 the holder is shown containing a lamp socket provided with a pull chain 5, the socket also being constructed with a flaring mouthpiece 6 to receive said chain as said sockets are ordinarily constructed. The flaring mouthpiece 6 fits in the side projection

3 in the recess 2, as shown in Fig. 1, the socket being thus locked and held in position in the holder by said bayonet joint recess and the threaded pin 4. In order to fit the lamp socket in the holder 1 the chain 5 is

first passed through the recess 2 from the inside of the holder 1 outwardly and then the mouthpiece 6 is fitted in place by manipulating the socket so that said mouthpiece will pass through the recess in said holder 60 and come into position with its flaring end outside of the same, as shown in Fig. 1.

In Fig. 2 the holder is shown without any lamp socket in it, or else with an ordinary wall socket without either chain pull or key. 65 In Fig. 3 the holder 1 is shown provided with a lamp socket having a key 8. This lamp socket is inserted into the holder 1 and the key 8 caused to pass through the slot 2 so as to come into position outside of the holder 1 70 while the lamp socket is in position inside of the same. The key 8 may be turned as desired to light and put out the lamp.

In Fig. 1 I show the holder 1 provided with a spring clip 10 for detachably supporting a globe or shade. This clip 10 preferably consists of a metallic wire bent as shown in Fig. 5 so as to have a loop portion 11 and two side portions 12 with overlapping ends 14 provided with loops or eyes 15 which 80 project through the flange 17 at the lower end of the holder 1, slots 18 being provided for said loops 15 to permit lateral movement thereof. By pressing the members 15 together the side portions 12 of the spring 85 clip are separated from one another, thus enlarging the circle formed by said spring, and when said members 15 are released the sides 12 come together. In this way a globe or shade inserted into the flange 17 may be 90 detachably engaged and disengaged.

Changes and modifications may be made without departing from the spirit of the invention.

What I claim is:

1. A device of the class specified comprising a shell or casing adapted to receive a lamp socket and provided with an aperture having a length at least equal to the length of the key of a key incandescent lamp socket 100 and having a side enlargement at one end, said enlargement being adapted to receive the chain aperture projection of a chain pull incandescent lamp socket.

2. A device of the class specified comprising a shell or casing having an open end to receive a lamp socket, and having a longitudinally extending slot having a length at least equal to the length of the key of a key incandescent lamp socket and provided with 105

2
a side enlargement, in combination with a lamp socket provided with a chain pull and having a projecting member associated with said chain, said lamp socket being inserted 5 in said shell or casing and having said projecting member fitting in the side enlargement of said slot.

3. A device of the class specified comprising a shell or casing adapted to receive an 10 incandescent lamp socket and provided with a slot having a length at least equal to the length of the key of a key incandescent lamp

socket and having a side enlargement at one end, said enlargement being adapted to receive the chain aperture projection of a chain 15 pull incandescent lamp socket, said enlargement being at the end of the slot farthest from the open mouth of the shell or casing.

In witness whereof, I hereunto subscribe my name this 23d day of July A. D., 1915.

JAMES WILLIAMSON.

Witnesses:
